keeper wires 32 from bending, suitable loops 42 may be provided thereon to rotatably engage the offset portions of the rod 22 disposed in the recesses 26, as shown in Figure 1.

It is believed that the advantages and use of the invention will be clearly apparent from the foregoing disclosure and, accordingly, further discussion thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

In a nestable container, the combination of a substantially rectangular receptacle including a bottom and upwardly and outwardly extending side walls having rolled upper edge portions to provide a perimetric bead, a reinforcing rod positioned in said bead, the bead on two opposing side walls being provided with recesses whereby at least two longitudinally spaced portions of said rod are exposed on each of the two opposing side walls, and a pair of keeper members provided on the respective opposing side walls and each consisting of an angulated wire provided at opposite ends thereof with eyes rotatably mounted on said spaced portions of said rod whereby said wires may be swung from an inoperative position outside said receptacle and spaced therefrom to an operative position inside the same, intermediate portions of said wires in an opera-

tive position affording substantially vertical shanks engageable with inner surfaces of the respective opposing side walls and substantially U-shaped inwardly projecting support elements whereby another like receptacle may be supported in a substantially spaced position above said bottom, said spaced exposed portions extending outwardly from said side walls and being angulated in a horizontal plane to afford outwardly offset hinge members to rotatably receive said eyes, and said support elements having short shanks comprising intermediate portions of the elements, said shanks extending substantially normal to portions of the elements at either end of the shanks and engaging inner surface portions of said side walls when in operative positions, said shanks being offset from said eyes a distance substantially equal to the outward extension of the exposed spaced portions, all portions of said elements being spaced from said side walls when in inoperative position so that the elements are not ordinarily fouled by expanding food products during the baking of the same in said container.
